PLEAT HOLDING OR CLAMPING DEVICE

Simon Esecson, Malden, Mass.

Application July 9, 1946, Serial No. 682,402

9 Claims. (Cl. 38—12)

1

This invention relates, as indicated, to a pleat holding or clamping device for pressing machines, but has reference more particularly to a device of this character which facilitates the pressing of pleats in skirts and other garments.

Devices of this nature have heretofore been proposed, such, for example, as those shown in U. S. Patents 1,501,044 and 1,764,808. These devices, are, in general, unsatisfactory, since they project above the ironing board to such an extent that they interfere not only with ironing by an ordinary electric or flat iron, but also prevent bringing the upper or movable board or member of an ordinary pressing machine down into pressing contact with the skirt, where such machines are employed for ironing. These devices, moreover, are so complicated and cumbersome that they can only be used with difficulty, and their construction makes them expensive to purchase as well as repair.

The present invention has as its primary object the provision of a device of the character described, which is so constructed as to have little or no portion thereof which projects above the upper surface of the pleats to be pressed, so that interference with the pressing operation in a pressing machine is virtually eliminated.

Another object of the invention is to provide a device of the character described, which is extremely simple in construction, consisting of a minimum number of easily manufactured and readily assembled parts.

A further object of the invention is to provide a device of the character described, which is inexpensive and readily adapted for production in commercially desirable quantities.

A still further object of the invention is to provide a device of the character described which is a highly efficient and effective aid in the pressing of pleated skirts and other pleated garments.

Other objects and advantages of the invention will be apparent during the course of the following description.

In the accompanying drawings, forming a part of the specification, and in which like numerals are employed to designate like parts throughout the same,

Fig. 1 is a plan view of an ironing board, showing the use of the device of the present invention;

Fig. 2 is a cross-sectional view, taken on the line 2—2 of Fig. 1;

Fig. 3 is a perspective view of the device;

Fig. 4 is a perspective view of one of the pleat clamping elements;

2

Fig. 5 is an enlarged fragmentary cross-sectional view, illustrating the manner in which the pleat-securing member extends through a pleat;

Fig. 6 is a perspective view of one of the members which is used for fastening down the waistband of the garment, and

Fig. 7 is a fragmentary perspective view, showing a modification of the pleat-clamping element of Fig. 4.

10 Referring more particularly to Figs. 1 to 6 inclusive of the drawings, the reference numeral B designates an ironing board, which may be an ordinary hand ironing board of the well-known type, or the lower or garment supporting board 15 of an ordinary pressing machine, such, for example, as a pressing machine of the Hoffman type. Such an ironing board comprises, in the usual case, a body or frame, a certain amount of padding P which overlies the top and edges of the frame, and a fabric covering F for holding the padding in place.

The garment, designated G, in this case, a skirt having a waistband W and having pleats P', is draped or laid over the ironing board B in the usual manner, and a series of flat metallic elements 1, having thumbtacks 2 welded thereto adjacent the ends, is employed to secure the waistband W to the board B. For this purpose, the points 2' of the thumbtacks 2 are pushed 20 through the waistband and into the padding P of the board, as clearly shown in Fig. 1. This effectively clamps the waistband to the board.

The device which forms the subject matter of the present invention comprises a metallic strap 3, having downturned ends 4, to which the ends of a tension spring 5 are connected, the spring being thus disposed substantially parallel with and in spaced relation to the upper horizontal portion 3 of the strap. The strap 3—4 is 35 preferably made from sheet steel of about 15 gauge.

The portion 3 of the strap is provided with a centrally disposed longitudinally-extending slot 6.

Secured to the portion 3 of the strap, as by 40 means of rivets 7, which extend through the slot 6, is a multiplicity of flat, substantially rectangular supporting elements 8, preferably formed from spring steel, of about 21 gauge.

Each of the elements 8 has a loop 8a struck 45 upwardly therefrom and under which is inserted one end of a U-shaped pleat-securing member 9, the arms of which overlie and bear against the element 8 and are turned downwardly, as at 9a to provide points 9b. The portions 9a of these 50 pleat-securing members extend downwardly

through perforations provided therefor in the elements 8.

The riveted connection of the elements 8 to the strap 3 is such that each of the elements can be slid to any desired position along the slot 6, and can also be rotated about the rivet, as an axis, to a position substantially parallel with the strap 3 or alongside the strap. Moreover, the slot 6 is open at the ends, as shown in Fig. 3, so that in the event any of the elements 8 or members 9 become damaged, it may be easily slid out of the slot and repaired or replaced.

In using the device which has been described, to facilitate the pressing of the pleats in the skirt G, the hem portion of the skirt is placed in approximately the position it will occupy during the pressing operation, and the strap 3-4 is then moved along the wider end of the pressing board to a position closely adjacent to, but in spaced relation to the hem of the skirt. The stretch of the spring 5 permits this movement of the strap, and, at the same time, the springs maintain the portion 3 of the strap flat against the upper surface of the board.

After the strap 3 has been thus positioned, each pleat of the skirt is folded into proper position for pressing, and as each successive pleat is thus folded, the operator will push the pointed portions 9a of one of the pleat-securing members 9 through the pleat and into the padding of the board until the element 8 lies flat against the pleat, as clearly shown in Fig. 5. The springy character of the element 8 facilitates bending of this element for the purpose of properly positioning the element and pushing the pointed portions 9a into the pleat and padding.

After all of the pleats have been thus secured or clamped into place, the operator will then bring the upper ironing board of the pressing machine down on the skirt, and thereby presses all of the pleats in a single operation, and in a highly efficient and effective manner.

Due to the fact that the strap 3, as well as the members 8 lie substantially flat against the ironing board or the garment, and the fact that the device has no portions thereof which project to any extent above the upper surface of the pleats, no interference is interposed by the device to the pressing operation, and the garment can be quickly and easily pressed.

Moreover, the device is extremely simple in construction, consists of a minimum number of easily manufactured and readily assembled parts, is inexpensive and is readily adapted for producing in commercially desirable quantities.

After the pressing has been completed, the elements 8 can be lifted to withdraw the pointed portions of the members 9 from the pressing board and garment, the springy character of the members 8 facilitating such withdrawal. After this, the members 8 can be rotated to the position shown in Fig. 3, in which the points 9b rest on the strap 3, at opposite sides of the slot 6. The device can then be quickly and easily slipped off the ironing board.

In Fig. 7 I have shown a modified form of the pleat clamping element shown in Fig. 4. In this case, the element consists of a flat supporting element 10, preferably formed of spring steel, and having a rivet 11 secured to one end, which functions in the same manner as the rivet 1 of the previously described form of the invention, and a pleat-securing member 12 at its other end. The member 12 is preferably in the form of a thumbtack which is welded to the element 10 and

has a point 13 which functions in the same manner as the points 9b of the previously described form of the invention.

It is to be understood that the forms of my invention, herewith shown and described, are to be taken as preferred examples of the same, and that various changes in the shape, size and arrangement of parts may be resorted to, without departing from the spirit of my invention, or the scope of the subjoined claims.

Having thus described my invention, I claim:

1. In a device of the character described, a strap member adapted to overlie a pressing board, spring means for securing said strap member to said board, elements riveted to said strap at spaced intervals, and pleat-securing members supported by said elements, said members having pointed portions adapted to be pushed through the pleats of a garment and into said board, said elements normally disposed in substantially the same plane as said strap member.

2. In a device of the character described, a strap member adapted to overlie a pressing board, means securing said member to said board, while permitting movement of said member to a selected position along said board, elements secured to said strap member at spaced intervals, said elements being movable along said strap member and being also pivotally movable with respect to said strap member, each element having a pleat-holding pin associated therewith.

3. In a device of the character described, a strap member adapted to overlie a pressing board, means securing said member to said board while permitting movement of said member to a selected position along said board, said member having a longitudinally-extending slot therein, elements extending from said strap member at spaced intervals, rivets extending through said members and through said slot, said rivets permitting movement of said elements along said slot, and pivotal movement of the elements relatively to said strap member, and pleat-holding pin members carried by said elements.

4. A device, as defined in claim 3, in which said elements are formed of spring steel.

5. A device, as defined in claim 3, in which said pin members have downturned pointed portions adapted for entry into the pleats of a garment.

6. In a device of the character described, a strap member adapted to overlie and be secured to a pressing board, said member being movable to a selected position along said board, elements extending beyond one side of said strap member and movable along said strap member, each element having a pleat-holding pin associated therewith.

7. In a device of the character described, a strap member adapted to overlie and be secured to a pressing board, elements extending beyond one side of said strap member and movable to selected positions along said strap member, said elements having pointed portions adapted to be pushed through pleats of a garment and into said board, said elements normally disposed in substantially the same plane as said strap member.

8. In a device of the character described, a strap member adapted to overlie a pressing board, said member being movable to a selected position along said board, said member having a longitudinally-extending slot therein, elements extending from said strap member at spaced intervals, means extending from said elements and through said slot, said means permitting move-

ment of said elements along said slot, and pleat-holding pin members carried by said elements.

9. In a device of the character described, a strap member adapted to overlie a pressing board and be retained on said pressing board at a selected position thereon, elements slidably secured to said strap member, whereby said elements may be moved longitudinally of said strap member, and a pleat-holding pin associated with each of said elements, whereby to transfix a garment on said board.

SIMON ESECSON.
